UNITED STATES PATENT OFFICE.

JOHN G. PORTER, OF WEAVERVILLE, CALIFORNIA.

ROTARY ENGINE

1,347,709.

Specification of Letters Patent.

Patented July 27, 1920.

Application filed July 11, 1919. Serial No. 310,045.

To all whom it may concern:

Be it known that I, JOHN GERALD PORTER, a citizen of the United States, and a resident of Weaverville, in the county of Trinity and 5 State of California, have invented certain new and useful Improvements in Rotary Engines, of which the following is a specification:

My invention relates to improvements in 10 engines, and more particularly to rotary engines which are operated by direct and expansive pressure of a motive fluid or gas introduced therein and has for its object to produce an engine which shall be simple in 15 construction and operation, and in which the operation is wholly internal.

Another object is to produce such an engine having an adjustable expansion control.

20 With these and other objects in view, my invention consists in certain novel features of construction, arrangement and combination of parts as will hereinafter be fully described and pointed out in the claims, reference being had to the drawings, in which—

Figure 1 is a side elevation of my invention, showing the exterior appearance and arrangement of the feed and exhaust mechanism;

30 Fig. 2 is a vertical longitudinal section through the casing or stator;

Fig. 3 is a transverse section through the engine, taken on line 3—3 of Fig. 2;

Fig. 4 is a detail section of the abutment 35 valve stem guide; and

Fig. 5 is a perspective view of a valve gear rod for controlling inlet and exhaust valves.

Referring more particularly to the drawing, I provide a casing or stator which 40 comprises two circular flanged members A and A¹, each having two or more projections B and B¹ radiating from the periphery downwardly and shaped to provide an annular groove C of semi-circular section of the largest possible diameter within the outer flange D, said members being fitted and matched and firmly secured together by 45 bolts d passing through the flanges at proper intervals.

50 The members A and A¹ when so secured together constitute a stator having an annular chamber E corresponding to the ordinary steam cylinder, said chamber having circular cross section and having radiating

55 therefrom the recesses or pockets F which

extend into the radial extensions or legs B and B¹ before mentioned.

The members A and A¹ are each depressed in the central portion to a depth sufficient to receive one-half the thickness 60 of the rotor disk and machined to a true face; the inner faces of the stator member are provided with a circular groove A² adjacent its periphery in which a gasket A³ is placed to render the casing gas-tight. 65

The members A and A¹ are provided with an opening A⁴ in the center to receive the shaft S, suitable anti-friction boxing s being held within the hub A⁵ formed integral with the casing plates. Suitable oil cups G 70 are applied to the hub members, whereby proper lubrication of the parts may be secured.

The rotor hereinbefore mentioned is a 75 steel disk H having a hub h at its center which fits true in the pressed out portions of the casing plates before referred to (see Fig. 3), so that it (the rotor) fits accurately between the aforesaid casing members.

The disk rotor is so shaped that it has two 80 or more projecting portions which extend to the outer rim of the annular chamber and form double cams H¹, H², a space being left between each set of double cams, in which space the piston heads H² are placed, and 85 securely bolted to the cams. The piston heads which are circular in cross section have a moving fit in and approximately fill the annular chamber, being provided with piston rings h¹ to prevent passage of gases 90 alongside the piston head.

The ends or working faces of the piston heads are substantially flat and are in radial planes that converge to the center of the supporting shaft S. 95

As hereinbefore stated, the casing is provided with mating members which produce radially projecting legs, one member of the legs, B, being extended to form feet B² by which the engine assembly is fastened to a 100 bed or frame or other suitable foundation.

The recesses or pockets are provided in the radiating legs for the reception of gates or abutments I which reciprocate radially across the opening in the annular steam 105 cylinder at this point, completely closing the same, and preventing back pressure of the motive fluid.

The form of these pockets is rectangular in its main section for the reception of the 110

gates or sliding abutments, and these pockets widen out into additional pockets or recesses F^1 , which extend at right angles at each side of the main gate recess, these side recesses being provided for the reception of the fenders on opposite faces of the gate or sliding abutment, when said abutment is forced into the main pocket by the projecting cams on the piston head. These fenders 5 F^2 are plates generally triangular in shape and are provided with slots F^3 in which are mounted the plungers F^4 , which are pivotally connected to a valve stem F^5 fitted to slide in a bore in the sliding gate or abutment; the valve stem carries a beveled valve 10 held to the reduced end of the valve stem by a nut and said valve fits a beveled valve seat in the lower end of the abutment or gate, a coiled spring f surrounding the valve stem between the valve and perforated 15 guide collar f^1 held in place within the bore of the abutment by a set screw f^2 as seen in Fig. 2.

It will be noted that the plungers diverge 20 and extend through the opposite fenders of each abutment so that they will project into the path of the cams on the faces of the heads.

The abutments are normally forced out 25 of the pockets into the path of the piston heads by pressure of the motive fluid admitted behind the valve heads through the port J , this pressure also keeping the valves to their seats. This port leads from the 30 pipe J^1 which is connected by a T-union K with the main motive fluid supply pipe L which extends upwardly and is coupled up with the motive fluid supply reservoir, a valve L^1 being placed in the supply pipe to 35 control the supply of steam or shut it off entirely.

The inlet pipes and exhaust pipes are represented by M and N , respectively, the inlet pipe leading into the annular chamber 40 at the ports N^1 and the exhaust pipe communicating with the said annular chamber by the ports M^1 .

The inlet pipe and the exhaust pipe are provided with three-way valves N^2 and M^2 45 having stems to which are connected crank levers N^3 and M^3 , the crank levers being pivotally connected to a rocker rod O which is to be manipulated by the engineer, to operate the valves, to admit steam, exhaust same, shut off and to set the valves for reversing the engine.

Within the wall of the annular chamber at each side and communicating at one end with the inlet ports are the curved expansion grooves P which are controlled by slides Q fitting said grooves and operated from without the casing by pins or knobs R projecting through curved slots R^1 in the 55 walls of the casing; these slides are, of course, fitted gas-tight in the arcuate

grooves so that there will be no escape of the motive fluid through the slots in which move the pins.

The rotor is keyed to the shaft and on the said shaft S is also keyed a band pulley T 70 by means of which pulley the power can be belted off to drive machinery.

In the space between the two abutments is a space that I designate as a lock between abutments.

The abutments which are to be two or more in number are for the purpose of preventing back pressure, so that the power medium cannot have a tendency to force the piston heads backward to the nearest exhaust, and these abutments are actuated by jets of steam, air or gas under pressure connected with outside circulation and controlled by valves (not shown).

Functioning of the mechanism is as follows: The piston head advancing, the abutment being forced out of its pocket by pressure below the valve in the bore thereof, the cam on the face of the piston head contacts with one of the plungers F^4 ; this forces 85 open the valve F^5 and releases pressure from behind the abutment, whereupon the abutment recedes into the pocket or recesses, and the piston head passes over the same.

In the walls of the abutments that face 90 each other just beneath the fender on that side is disposed a small passage 10 which communicates with the bore of the abutment, both of these passages being closed when the abutments are forced entirely 100 within their pockets, but as soon as the cam of a piston head contacts with a plunger of an extended abutment the valve in the abutment being unseated, communication is established between inside of the pocket and 105 fluid pressure therein will rush through the bore of the abutment and discharge through the passage 10 into the lock between the abutments.

To reverse the engine, the motive fluid is 110 directed by the three way valves hereinbefore referred to, which valves are worked in unison by means of the rocker bar which will be attached to and thrown by an ordinary lever.

The meeting faces of the two members of the stator are provided with annular grooves just within the inner circumference of the annular chamber; in which are placed gaskets a which bear against the rotor and 120 prevent passage of steam from the steam chamber between the members of the stator.

I claim:

1. A rotary engine including a stator comprising an annular motive fluid chamber, 125 circular in cross section, and abutment pockets or recesses radiating from the periphery thereof and communicating with said annular chamber, a rotor rotatably mounted within said stator and comprising a disk 130

- and radially disposed piston heads fitting within said annular chamber, cam plates projecting from the ends of said piston heads valved abutments slidably mounted in the radial pockets of the stator, motive fluid pressure inlet and outlet supply means communicating with said annular chamber, the inlet means also communicating with the abutment pockets behind the valved abutments and forcing them into the annular chamber, and means carried by said abutments to open the valve therein upon impact with a piston head, whereby pressure is released behind the abutments and through the same into the annular chamber between the abutments, and to permit the abutments to recede into their pockets.
2. In a rotary engine, in combination, a stator including an annular motive fluid pressure receiving chamber, abutment pockets radiating therefrom, valved fluid pressure projected abutments in said pockets, and means carried by said abutments controlling the valve means and actuated by the rotor to relieve said fluid pressure in the abutment pockets whereby the abutments are forced within their pockets by said rotor.
3. In a rotary engine, the combination with a stator having radial abutment pockets, and an annular circular motive fluid chamber, a rotor carrying piston heads, fitting said annular chamber, abutments slidably mounted in said pockets, means for introducing motive fluid behind the said abutments, and means carried by the abutments for releasing the motive fluid behind the same to the aforesaid annular motive fluid chamber.
4. In a rotary engine, the combination with a stator having an annular chamber, a motive fluid chamber and abutment pockets radiating therefrom, a rotor having piston heads fitting within said annular chamber, means for introducing motive fluid into the annular chamber, means for introducing motive fluid into said pockets behind the abutments to project the abutments across the path of said piston heads, and means carried by the abutments for releasing pressure behind said abutments.
5. In a rotary engine, the combination with a stator having an annular motive fluid chamber therein, and radially disposed abutment pockets projecting therefrom, abutments slidably mounted in said pockets, said abutments having a central bore, a valve at the rear end of said abutments and closing the bore at that end, means for introducing motive fluid to the abutment pockets at the rear end of the abutments, such motive fluid forcing the valve to its seat and closing the rear end of the bore, a rotor mounted within said stator and having piston heads traveling in the annular chamber, and means carried

ried by said piston heads for unseating said valve to release pressure from behind the abutments to the annular chamber and between the abutments.

6. In a rotary engine, the combination with a casing having radially disposed chambered legs extending from the periphery thereof, abutments slidably mounted in the chambers of said legs, said abutments including a centrally bored stem, means for introducing a motive fluid into said leg chambers at the rear of the abutment stand, a spring actuated valve stem projecting from the valve through the bore of the stem, perforated angular fenders projecting from opposite sides of the stem at its forward end, plungers connected to said valve stem and projecting through the perforations in the fenders, and a rotor carrying piston heads having cam projections on the opposite faces thereof adapted to engage the aforesaid plungers to release pressure through the stem of the abutments into the annular chamber between the abutments, and means for admitting and exhausting motive fluid to the annular chamber, and behind the valve stem of the abutments.

7. In a rotary engine, the combination with a stator having an annular motive fluid chamber therein, and abutment chambers radiating therefrom, a shaft mounted in said casing, a rotary disk rigidly secured to said shaft and adapted to rotate within said stator, radial piston heads carried by said disk and fitting within said annular chamber, the abutments slidably mounted within said abutment chambers and adapted to be forced into the abutment chambers by the piston heads, inlet ports extending into said annular chamber, and expansion grooves extending from said inlet ports and lying within said annular chambers, and means for controlling the area of said expansion grooves.

8. In a rotary engine, the combination with a casing having an annular motive fluid chamber, and abutment pockets radiating therefrom, a shaft mounted in said casing and a disk secured thereto and revolving within said casing, piston heads carried by said disk at its periphery and fitting within the said annular chamber, abutments slidably mounted in said abutment pockets and adapted to be forced into the pockets by said piston heads, inlet and exhaust ports leading into said annular chamber at one side of the line of said abutment pockets, arcuate expansion grooves extending from said inlet and exhaust ports within the annular chamber, and means for varying the area of the inlet expansion groove.

9. In a rotary engine, the combination with a casing having an annular motive fluid expansion chamber therein and abutment chambers projecting therefrom and

communicating with the said annular chamber, fluid pressure actuated abutments slidably mounted in said abutment chambers, said chambers having lateral recesses at its forward end, said abutments including a hollow stem and angular fenders at its front end, said fenders adapted to be housed in said lateral recesses when the abutment is forced into their chambers, the forward end 10 of said abutments having diverging openings therethrough and plungers mounted in said openings, a valve stem connected to said plungers, a valve at the rear end of said stem, and controlling the rear end of the hollow stem, a rotor mounted in said casing 15 and having piston heads fitting within said

annular chamber, and adapted to contact with said plungers and unseat the aforesaid valve at the rear of the abutment stems, inlet and outlet ports leading into the annular chamber between abutments, and to the abutment chambers at the rear of the abutments, a source of motive fluid supply, piping leading from the same to the aforesaid ports, and three-way valves for controlling said pipes between the source of supply and the inlet and exhaust ports.

JOHN G. PORTER.
